UNITED STATES PATENT OFFICE.

WALENTY NALEPKA, OF SOUTH OMAHA, NEBRASKA, ASSIGNOR OF ONE-SIXTH TO PAUL ZUREK, ONE-SIXTH TO KAROL SIEWNAK, AND ONE-SIXTH TO STANLEY WIERNEK, ALL OF SOUTH OMAHA, NEBRASKA.

METALLIC TIE.

1,028,484.

Specification of Letters Patent.

Patented June 4, 1912.

Application filed September 1, 1911. Serial No. 647,179.

To all whom it may concern:

Be it known that I, WALENTY NALEPKA, a subject of the Emperor of Austria-Hungary, residing at South Omaha, in the 5 county of Douglas and State of Nebraska, have invented certain new and useful Improvements in Metallic Ties, of which the following is a specification, reference being had therein to the accompanying drawing.

10 This invention relates to metallic ties and rail fasteners, and the primary object of my invention is to provide extremely light and durable ties that can be manufactured at a minimum cost and easily tamped and anchored in a road bed.

Another object of this invention is to furnish a tie with rail fasteners possessing the same gripping power as spikes, said fasteners being arranged whereby they can be repeatedly adjusted to compensate for vibrations.

A further object of my invention is to furnish metallic ties with fasteners that will preserve the alinement of rails and prevent 25 lateral and vertical displacements.

These and such other objects as may hereinafter appear are attained by a mechanical construction that will be presently described and then claimed.

30 Reference will now be had to the drawing, wherein—

Figure 1 is a perspective view of ties in accordance with this invention, showing certain inner fasteners removed; Fig. 2 is a 35 longitudinal sectional view of a portion of one of the ties and the fasteners thereof; Fig. 3 is a cross sectional view taken on the line III—III of Fig. 2, and Fig. 4 is a perspective view of a detached inverted inner fastener.

Ties in accordance with this invention comprise flat metallic slabs 1, and each tie has the outer end thereof provided with outer rail fasteners 2. These fasteners are 45 riveted or otherwise connected, as at 3, to the tie 1, and each outer fastener has an inwardly projecting overhanging flange 4 adapted to engage the outer base flange 5 of a rail 6. The outer fasteners are permanent 50 and determine the gage of a track, said outer fasteners preventing the rails from spreading or becoming vertically displaced.

To retain the outer base flanges of the rail 6 in engagement with the outer fasten-

ers of the tie, I employ inner fasteners 7. 55 The inner fasteners are somewhat similar to the outer fasteners, each fastener having an overhanging flange 8 to engage an inner base flange 9 of the rail 6. Each inner fastener has a depending rectangular block 10 adapted to fit in an elongated opening or slot 11 provided therefor in the tie 1. The lower part of the opening or slot 11 is enlarged or of a greater width than the upper part of the slot to provide horizontal 60 shoulders 12. Engaging these shoulders and snugly fitting in the lower part of the opening or slot 11 is a bolt head 13 and the walls of the opening or slot prevents said head from rotating. The bolt carried by the head 70 13 extends upwardly through a vertical opening 14 provided therefor in the block 10 and the inner fasteners 7, said bolt shank having the upper end thereof threaded, as at 15 to receive a nut 16. The slot or opening 11 is of a greater length than the block 10, consequently the inner fastener can be shifted inwardly to firmly grip the inner base flange 9 of a rail, should the same become loose.

It is thought that the manner of installing the ties and rail fasteners will be apparent without further description, and I reserve the right to make such changes in the structural details as fall within the scope 85 of the appended claim.

What I claim is:

A metallic tie comprising a rectangular relatively thin slab for supporting a pair of rails, plates fixedly secured to the upper 90 face of said slab at each end thereof and each provided with an inwardly extending portion capable of overlapping one side of the base of the rail for securing the same upon the slab, said slab further provided 95 in proximity to each of said inwardly extending portions with a centrally disposed longitudinally extending rectangular slot, the lower portion of said slot being of greater width than the upper portion thereby providing the side walls of the slot with shoulders, inner fasteners mounted upon 100 said slab and each consisting of a plate provided with outwardly projecting flanges capable of overlapping the outer sides of 105 the bases of the rails for maintaining them in position upon the slab, rectangular blocks integral with the lower face of said inner

fasteners centrally thereof and extending into said slots, said inner fasteners provided with openings projecting therethrough and through said blocks, bolts extending upwardly through said blocks and fasteners and having their heads engaging said shoulders to prevent the withdrawal of the bolts upwardly through said slots, and means mounted upon the upper ends of said

bolts and engaging said fasteners for fixedly securing these latter and the bolts in position upon the slab. 10

In testimony whereof I affix my signature in the presence of two witnesses.

WALENTY NALEPKA.
